UNITED STATES PATENT OFFICE.

ROBERT DUNCAN CONNOR AND ROBERT PERCIVAL SLINGER, OF MANCHESTER,
ENGLAND.

APPARATUS FOR HAMMERING THE DIES OF WIRE-DRAWING MACHINES.

1,310,968.

Specification of Letters Patent.

Patented July 22, 1919.

Application filed February 4, 1919. Serial No. 275,033.

To all whom it may concern:

Be it known that we, ROBERT DUNCAN CONNOR and ROBERT PERCIVAL SLINGER, both subjects of the King of Great Britain and Ireland, and residents of Manchester, England, have invented an Improved Apparatus for Hammering the Dies of Wire-Drawing Machines, of which the following is a specification:

- 10 This invention refers to a new or improved apparatus or machine for mechanically hammering the dies used in wire drawing machines preparatory to reforming or resetting the hole in the die.
- 15 According to the invention, the machine is formed with a horizontal rotary disk or turn-table, whereon may be placed the die to be hammered, the die fitting a central rectangular recess in the top of the table.
- 20 Supported by suitable carrier mechanism above the said turn-table is a hammer, preferably pneumatic, which is arranged with its longitudinal axis lying at an angle to, and in the same plane as the axis of the hole
- 25 in the die. By suitable gearing the turn-table and die are rotated, while by suitable cam and eccentric gear the hammer is first lowered on to the die, and then traversed across the face of the die from a point near to its outer edge to a point near the hole in the die and back again. After the die has been hammered the cam and eccentric gear serve automatically to raise and move back the hammer clear of the die. Through suitable belt
- 30 fork trip gear the hammer carrier mechanism, in drawing the hammer back, serves to stop the machine, the attendant moving the driving belt on to the driving pulley to restart the machine. When a pneumatic ham-
- 35 mer is used means are provided which allow the air inlet valve of the hammer to partly close as the hammer approaches the hole in the die, and thereby reduce the force and number of the blows, while as the hammer moves outward away from the hole, the valve is reopened and the force and number of the blows increased.

Upon the accompanying drawings,

Figure 1 is a side elevation of the machine.

Fig. 2 is a side elevation of the opposite

side of the machine to that of Fig. 1 and illustrating more particularly the movements of the hammer carrying frames.

Fig. 3 is a plan of Fig. 2.

Fig. 4 is a sectional elevation of the turn-table *per se*; and Fig. 5 is a plan of the turn-table.

In the preferred construction, as illustrated in the drawings, the machine comprises a fixed bed part *a*. At the forward end is arranged a vertical shaft *b*, fitted with a bevel wheel *c* near to its lower end, supported in a foot step bearing *b'*, and at its upper end fitted with a large circular plate *d* forming the aforesaid turn-table. Extending horizontally below the machine bed is a shaft *e* provided with a bevel pinion wheel *f* which meshes with the bevel wheel *c* on the vertical shaft *b*. Said horizontal shaft *e* is driven through suitable reducing gear comprising the small pulley *g*, belt *h*, and large pulley *i* on the driving shaft *j* which is fitted with fast and loose belt pulleys *k*, or a clutch.

At the rear of the machine is journaled a lever *l*, which extends upward, and at its upper end is pivotally connected to one end of a substantially horizontal and elongated parallel-sided frame *m*. Such frame consists of two long bars connected at intervals to each other, see Fig. 3. Between the extremities of the frame at the front end of the machine is mounted a pneumatic hammer *n*, the hammer body being pivotally and bodily adjustable between the said extremities of the frame and adapted to assume, and be firmly held, at an angle of about 110° to the longitudinal axis of the said frame, so that it assumes an angle of about 10° to the axis of the hole in the die when in the operative position. A flexible air pipe *o* extends from the top of the hammer to an air valve *p* at the rear of the machine, the valve being connected, through an ordinary pipe *q* and air reservoir, to a compressor.

Upon the machine bed *a* and below the said frame *m* is journaled a cross shaft *r* which through suitable worm and worm wheel gearing *j*, *r'*, receives rotary motion from the driving shaft *j* of the machine. Upon said cross-shaft *r* is fixed an eccentric

r^2 while said eccentric is adjustably connected by a suitable connecting rod s to the aforesaid lever l connected to the rear end of the frame m .

5 Upon the said cross shaft r is also a cam r^3 and bearing against said cam, through an anti-friction roller, is one arm of a bell-crank lever t , the axis of the lever being journaled in bearings t^1 below the machine bed (this latter being slotted), and the other arm of the lever extending forwardly below the machine bed. In the free end of such lever arm is a long regulating screw t^2 . Directly above the point of such screw is the 10 lower end of a stout rod u , which rod passes up through a swivel bearing u^1 mounted on the machine bed and at its upper end is pivotally connected to the said hammer-supporting frame m at a point toward the forward end 15 of the frame. The formation of the cam r^3 and the position of the parts are such that as the cross shaft r rotates (starting with the frame m raised), the frame and hammer are lowered until the hammer bears 20 upon the die v to be hammered when the hammer is moved once forwardly and backwardly half-way across the die, the cam r^3 during such period being practically neutral. Immediately, however, the hammer 25 completes its return movement, the cam r^3 commences to raise the hammer n clear of the die, and the eccentric r^2 completes the rearward movement.

The aforesaid screw t^2 on the arm of the 30 lever arm t , below the machine bed, allows of the hammer being lowered to different distances to suit the depth or thickness of the die to be hammered.

By varying the connection of the eccentric connecting rod s with the frame lever l i. e., by altering the point of connection along the slot l^1 the hammer may be adapted to move different distances according to the size of die to be hammered. The hammer 45 will usually lie at an acute angle of about 80° to the top face of the die when engaging the same, i. e., at an angle of about 10° to the axis of the hole in the die.

Mounted upon the axis w^1 of the belt fork 50 lever w of the driving pulley k is a lever arm x and balance weight x^1 . At its free end the lever arm is notched or stepped, whereby when the belt is on the fast pulley it may engage a shoulder y^1 on an adjacent trip 55 lever y . This trip lever y at its other end is provided with a screw y^2 the end or head of which lies near to the frame-carrying lever l . A rod z connected to a further lever arm z^1 on the belt-fork lever axis and extending 60 to the front of the machine serves to enable the driving belt l to be moved on to the fast pulley and the machine started, a handle z^2 being formed on the rod z for convenience of manipulation.

Upon the said shaft r which carries the eccentric r^2 is mounted a further cam r^4 . Against such cam bears a lever arm 2 which also bears against the spindle 3 of the air valve p , the formation of the cam r^4 being such that during the initial and final hammering operations, the lever 2 holds the valve p fully open, but as the hammer approaches the hole in the die v , the lever 2 allows the valve p to partially close and thus moderate the force and number of the blows 70 of the hammer, the cam r^4 and lever 2 re-opening the valve p as the hammer n approaches the outer end of its traverse. 75

The complete operation of the machine may be described as follows:

With a die placed in the sinking of the turn-table d and the machine started by manipulating the rod z , the lever arm x is engaged by the trip lever y which retains the driving belt l on the fast pulley k for 80 one cycle of movements. The cam r^3 first lowers the frame m until the point or nose of the hammer n rests upon the die after which the eccentric r^2 moves the hammer across the face of the die from a point near 90 the outside edge to a point near the hole. With the return movement of the eccentric, the hammer moves back in the same path across the die until it reaches the outside edge, when the cam r^3 finally raises it clear 95 of the die. During the forward movement of the hammer the cam r^4 gradually closes the air valve p to moderate the number and intensity of the hammer blows, to compensate for the decreased speed of the die surface being acted upon, said cam allowing the valve to open again during the reverse movement of the hammer.

During the whole of the time the hammer is acting upon the die it lies at an acute angle to the axis of the hole in the die, and therefore, the effect of the blows upon the die (as the latter rotates), is to force the metal toward the center of the die and thus reduce the hole. Upon the frame m and hammer n reaching their rearmost position the machine is stopped by the member l striking the lever y which trips the arm x and allows the balance weight x^1 to influence the belt fork and move the belt on to the 110 loose pulley k . A fresh die being placed in the sinking, the machine is restarted and the cycle of movements repeated.

The depth of the sinking in the turn-table will be rather less than half that of the die, 120 and in plan the sinking will be such as to allow the die to be an easy fit. A small raised cone or snug 5 in the center of the sinking and engaging the wider end of the hole in the die (see Fig. 4) serves to hold 125 the die central to the turn-table. With the hammer always resting upon the die during the hammering operation it is found that the

sinking is usually sufficient for keeping the die in position.

The pneumatic hammer will be of the ordinary calking tool pattern, giving a large number of blows per minute. That part of the hammer which touches the die is rotated by the die and table, and therefore, wears away evenly at all points of its circumference.

10 To clear the sinking of the turn-table of any scale or dust, a small air jet 4 is provided near the sinking.

What we claim is:

1. Apparatus for closing or reducing the holes in dies used in wire drawing machines comprising a rotary disk or turn-table adapted to receive the die to be hammered, a hammer arranged with its longitudinal axis lying at an acute angle to the top face of the die and in the same plane as the vertical axis of the hole in the die, and means whereby the hammer is automatically brought in contact with the face of the die to hammer the die transversely across its face and subsequently raised clear of the die, substantially as described.

2. Apparatus for closing or reducing the holes in dies used in wire drawing machines comprising a rotary disk or turn-table adapted to receive the die to be hammered, a hammer arranged with its longitudinal axis lying at an acute angle to the top face of the die and in the same plane as the vertical axis of the hole in the die, and means whereby the hammer is automatically lowered on to the die while the same is rotating and then transversed across the face of the die from a point near to its outer edge to a point near the hole in the die and back again and subsequently raised clear of the die, substantially as described.

3. Apparatus for closing or reducing the holes in dies used in wire drawing machines comprising a rotary table adapted to receive the die and rotate the same about an axis coincident with the hole therein, a hammer adapted to automatically engage the die face and be traversed across the same from a point near the outer edge to a point near the hole and subsequently moved clear of the die, together with means to vary the blows as the hammer advances to and recedes from the hole in the die, substantially as described.

55 4. Apparatus for closing or reducing the holes in dies used in wire drawing machines, comprising a rotary table adapted to receive the die and rotate the same about an axis coincident with the hole therein, a frame carrying a pneumatic hammer at its forward end and linked to the machine bed at its rear, an eccentric to reciprocate said frame, and cam controlled mechanism to lower the hammer on the die face during the forward stroke of the same and to raise said hammer clear of the die at or near the end of the rearward stroke, substantially as described.

forward stroke of the same and to raise said hammer clear of the die at or near the end of the rearward stroke, substantially as described.

5. Apparatus for closing or reducing the holes in dies used in wire drawing machines, comprising a rotary table adapted to receive the die and rotate the same about an axis coincident with the hole therein, a frame linked to the machine bed at its rear, a pneumatic hammer pivotally connected to the frame at its forward end, an eccentric to reciprocate said frame, and cam controlled mechanism to lower the hammer on the die face during the forward stroke of the same and to raise said hammer clear of the die at or near the end of the rearward stroke, substantially as described.

6. Apparatus for closing or reducing the holes in dies used in wire drawing machines, comprising a rotary table adapted to receive the die and rotate the same about an axis coincident with the hole therein, a frame linked to the machine bed at its rear, a pneumatic hammer pivotally connected to the frame at its forward end, an eccentric to reciprocate said frame, and cam controlled mechanism to lower the hammer on the die face during the forward stroke of the same and to raise said hammer clear of the die at or near the end of the rearward stroke, an air supply valve for said hammer and means for automatically controlling said valve, substantially as described.

7. Apparatus for closing or reducing the holes in dies used in wire drawing machines, comprising a rotary table adapted to receive the die and rotate the same about an axis coincident with the hole therein, a frame carrying a pneumatic hammer at its forward end and linked to the machine bed at its rear, an eccentric to reciprocate said frame, and cam controlled mechanism to lower the hammer on the die face during the forward stroke of the same and to raise said hammer clear of the die at or near the end of the rearward stroke, the die holding table having a sinking in its upper face to receive the die while the striker of the hammer remains in contact with and holds the die in the sinking during the hammering operation, said striker being free to be rotated by the die, substantially as described.

8. Apparatus for closing or reducing the holes in dies used in wire drawing machines, comprising a rotary disk or turn-table adapted to receive the die to be hammered, a hammer arranged with its longitudinal axis lying at an acute angle to the top face of the die and in the same plane as the vertical axis of the hole in the die, and means whereby the hammer is automatically lowered on to the die while the same is rotating and then traversed across the face of the die from a

point near to its outer edge to a point near the hole in the die and back again and subsequently raised clear of the die, means being provided for varying the horizontal and 5 vertical bodily movements of the hammer to suit the size of the die, substantially as described.

9. Apparatus for closing or reducing the holes in dies used in wire drawing machines, 10 comprising a rotary table adapted to receive the die and rotate the same about an axis coincident with the hole therein, a frame carrying a pneumatic hammer at its forward end and linked to the machine bed at its 15 rear, an eccentric to reciprocate said frame, and cam controlled mechanism to lower the hammer on the die face during the forward stroke of the same and to raise said hammer clear of the die at or near the end of the 20 rearward stroke, the die holding table having a sinking in its upper face to receive the die while the striker of the hammer remains in contact with and holds the die in the sinking during the hammering operation, said 25 striker being free to be rotated by the die, means being provided for varying the horizontal and vertical bodily movements of the hammer to suit the size of the die, substantially as described.

30 10. Apparatus for closing or reducing the holes in dies used in wire drawing machines, comprising a rotary table adapted to receive the die and rotate the same about an axis coincident with the hole therein, a frame carrying a pneumatic hammer at its forward 35 end and linked to the machine bed at its rear, an eccentric to reciprocate said frame,

and cam controlled mechanism to lower the hammer on the die face during the forward stroke of the same and to raise said hammer 40 clear of the die at or near the end of the rearward stroke, together with an air blast for clearing the table, substantially as described.

11. Apparatus for closing or reducing the 45 holes in dies used in wire drawing machines, comprising a rotary table adapted to receive the die and rotate the same about an axis coincident with the hole therein, a frame carrying a pneumatic hammer at its forward 50 end and linked to the machine bed at its rear, an eccentric to reciprocate said frame and cam controlled mechanism to lower the hammer on the die face during the forward stroke of the same and to raise said hammer 55 clear of the die at or near the end of the rearward stroke, the die holding table having a sinking in its upper face to receive the die while the striker of the hammer remains in contact with and holds the die in the sinking 60 during the hammering operation, said striker being free to be rotated by the die, means being provided for varying the horizontal and vertical bodily movements of the hammer to suit the size of the die, together 65 with an air blast for clearing the table, substantially as described.

In witness whereof we have hereunto set our hands in the presence of two witnesses.

ROBERT DUNCAN CONNOR.
